UNITED STATES PATENT OFFICE.

ERNEST JAMES JOHNSON, OF HANLEY, ENGLAND, ASSIGNOR TO JOHNSON BROTHERS
HANLEY (LTD.), OF HANLEY, ENGLAND, A CORPORATION OF ENGLAND.

DESIGN FOR A COVERED DISH OR SIMILAR ARTICLE.

Application filed January 2, 1923. Serial No. 4,789. Term of patent 3½ years.

To all whom it may concern:

Be it known that I, ERNEST JAMES JOHNSON, a subject of the King of Great Britain, and a resident of Hanley, in Staffordshire, England, have invented a new, original, and ornamental Design for Covered Dish or Similar Article, of which the following is a specification, reference being had to the accompanying drawing, forming part hereof.

Figure 1 is an elevation of an article of dinner ware; to wit, a covered dish, showing my new design, and

I claim:

The ornamental design for a covered dish or similar article, as shown.

ERNEST JAMES JOHNSON.
